Schuyler & Rockwell

Fire Engine.

No 21,449.

Patented Sep. 7, 1858.

UNITED STATES PATENT OFFICE.

I. S. SCHUYLER AND L. A. ROCKWELL, OF NEW YORK, N. Y.

HOSE-CARRIAGE.

Specification of Letters Patent No. 21,449, dated September 7, 1858.

To all whom it may concern:

Be it known that we, ISAAC S. SCHUYLER and LUCIUS A. ROCKWELL, of the city and county of New York, State of New York, 5 have jointly and together made certain new and useful Improvements in Apparatus for Extinguishing Fires; and we do hereby declare the following to be a full and exact description thereof, reference being had to the 10 annexed drawings, forming a part of this specification, representing the forward axle, bearing-wheels, &c., of a fire-engine, hose-cart, or other fire apparatus with our improvements attached, and in which—

15 Figure 1, is a plan view, Fig. 2 is a reverse plan view, Fig. 3 is a side elevation.

Letter A represents the axletree, B, the tongue with cross bar B² perforated with poles for the rope to pass through. The 20 tongue is connected to the axletree by angle braces C C which together with the T braces C' C' form a frame in which the reel shafts D, D, rotate.

E, E, are two reels attached to shafts 25 D, D, and to which the drag rope F is fastened, and on which it is wound.

G, G, are inclined toothed or ratchet wheels keyed on the shaft D, D.

H is a spring catch or stopper so arranged 30 by means of the slots, and screw bolts, H', H², as to be engaged with the teeth of the ratchet wheels G, G, or withdrawn at pleasure, and also so constructed as to yield while thrown into the teeth of the ratchet, 35 when the ratchet takes a backward motion, which it does when winding in the rope.

I, I, are clutches connected with the shafts D D by a slot and feather as usual in clutches.

40 J is a sliding bar or connecting rod secured in slides J', J', directly underneath the tongue, and jointed at one end with the toggle joint K, which is connected with the clutches, by the bent shifting arms L, L, 45 which take into grooves cut in the clutches.

M, M, are gear wheels running on shafts

D, D, and confined by a collar and screw nut D² on the end of the same, and perforated with holes to correspond with projections on the clutches.

50 N, N, are gear wheels gearing into the wheels M, M, and secured to the hubs of the bearing wheels O, O, which rotate on the axles P, P.

The operation of the various parts above 55 described is as follows, viz; The stop H is always thrown in, unless it is desired to let out rope, when it is withdrawn until the rope runs out by the pull on it, as far as desired, when it is again thrown in, and acts 60 to hold fast the reel and thereby pull the engine. When the rope requires to be taken in, the clutches are engaged with the wheels M, M, which, by means of the wheels N, N, attached to the bearing wheels O, O, cause 65 the reels to rotate continuously to wind in the rope, so long as sufficient power is exerted on the rope to move the engine forward, the stopper H yielding to the backward motion of the ratchet wheels.

70 What we claim as our invention and desire to secure by Letters Patent of the United States is—

1. The arrangement and combination of 75 two separate and independent rope reels respectively and separately with the bearing wheels rotating on the axle tree to which the reels are secured substantially as herein before described and substantially for the purposes herein before set forth.

80 2. The within described method of connecting and disconnecting the rope reels with the bearing wheels of a fire engine, hose cart or other fire apparatus for the purpose of taking in the drag rope while the apparatus is drawn by it.

ISAAC S. SCHUYLER.
LUCIUS A. ROCKWELL.
